(54) **MINERAL WATER, APPARATUS**

(76) Inventor: **Samuel Fahnestock**

Samuel Johnson, Stock.

Letters Patent.

The Schedule, referred to in these Letters Patent and making part of the same, containing a description in the words of the said Samuel Johnson, himself of his improvement in the apparatus for making Mineral Water.

The present apparatus used for preparing Mineral Water is a copper tinned vessel of an ellipsoidal form, which is first filled with water into which the carbonic acid gas is strongly forced by being pumped out of the reservoir where it is collected by means of a condensing pump through a stop cock and a copper tinned siphon, closed by a valve, when the water in said vessel is sufficiently charged with the gas and remains for sometime in said vessel, the carbonic acid acts upon the copper and tin, and decomposes some of it and forms the carbonate of copper and tin which is kept in a state of solution in the water & gives it a manorous taste of the metals. This has had very often disagreeable and pernicious effects on the stomach.

Improvement. The improvement of the subscriber is to effectually prevent the impurity which copper and tin gives to the artificial mineral water when prepared in those metals. By a means of a stone ware apparatus or vessel (or any other kind of vessel or apparatus, whose composition will not effect the purity of the mineral water) inclosed in a copper tinned vessel (or in any other kind of vessel, which will confine the gas to the interior vessel) open at its top.

Made of using it. This interior vessel must be filled about three fourths with pure water also the space between said vessels. The whole apparatus to be kept in a perpendicular position, the siphon made of copper (or any other metal which

which will not affect the purity of the water) is introduced into the mouth of the exterior vessel nearly down to the bottom of the interior vessel, the stopcock is screwed into the mouth of the exterior vessel, with a piece of leather between its shoulders, to make it perfectly air tight. The carbonic acid gas is strongly forced into the water, by being pumped out of the reservoir where it is collected by means of a condensing pump through the stopcock and dip tube, into the interior vessel closed by a valve, and the gas becomes diffused throughout the water in the interior & exterior of said inclosed vessels; which water is preserved by an equal pressure acting against the purity of the exterior vessel, retaining the impure water between said vessels, and the water in the interior vessel will be perfectly pure, and fully saturated with the carbonic acid gas, & will remain so until the whole is run off: Then unscrew the stopcock, and invert the whole apparatus, and the impure water between said vessels will discharge itself through the mouth of the exterior vessel. In this apparatus wine, cider and beer, may be impregnated with the carbonic acid gas to any degree; and also the solution of magnesia and soda as prepared perfectly pure in it, &c.
